UNITED STATES PATENT OFFICE.

PAUL B. MURPHY, OF NYACK, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed August 6, 1924. Serial No. 730,366.

To all whom it may concern:

Be it known that I, PAUL B. MURPHY, a citizen of the United States of America, residing at Nyack, in the county of Rock-
5 land and State of New York, have invented certain new and useful Improvements in Signaling Systems, of which the following is a full, clear, concise, and exact description.

10 This invention relates to signaling systems, and more particularly, to improved methods and means for signaling over transmission lines.

Under the present telephone practice involving the use of toll lines inter-connecting different exchanges, several methods of extending calls are employed. For example, in case a toll connection is to be extended automatically and can only be completed between two exchanges through one or more intermediate exchanges, the toll operator at the originating exchange must, after having connected manually to a toll line leading to the first intermediate exchange, set up the remainder of the connection by dialing one portion at a time of the toll code number representing the desired exchange, each portion representing an automatically established connection to a succeeding exchange, each succeeding portion being dialed only after the operator has received a signal to proceed. Thus, the speed of setting up a connection depends to a large extent on the individual operator's skill in attention to signals and her knowledge of the routes by which the distant exchange may be reached.

It is an object of this invention to eliminate the necessity for the toll operator to dial the toll code number in sections or know the route to be employed by a toll connection between two exchanges and to this end means is provided whereby the toll operator may establish a toll connection to a distant exchange by merely dialing once the complete toll code number, regardless of how many intermediate exchanges may be involved or what route is to be followed, and without having to pay any attention to any signals during the establishing of the connection.

Another object is to provide means whereby all dialing impulses and supervisory or controlling signals incidental to the establishing of a toll connection may be, as far

as signals between exchanges that is, over the toll lines are concerned, of a high frequency alternating current character. By employing this type of impulses it is immaterial what kind of toll lines are used 60 in this system for example, ordinary wire toll lines with or without repeater equipments, a channel of a carrier telephone installation, a radio telephone connection, composite lines or phantom lines may be 65 equally well employed without fear of any disturbing effects from the toll line signaling.

To obtain these objects according to one feature of the invention automatic switch- 70 ing equipments are provided at each exchange available to any toll operator in that exchange for selecting an idle toll line extending in the general direction of the desired exchange, that is, an idle switching 75 equipment may be selected and directly operated to select, hunt for and connect to an idle toll line in any one of a number of groups of toll lines over which the desired exchange may be reached.

80 Another feature of the invention is the provision of means in connection with said common switching equipments whereby the toll operator may selectively operate other local automatic switches at the exchange 85 to connect directly with a subscriber's line in the exchange.

Another feature of the invention is the provision of means in connection with said common switching equipments, whereby 90 high frequency signaling impulses incoming over toll lines terminating at an exchange may be utilized to select an idle outgoing toll line in any one of a number of groups of toll lines over which a distant 95 exchange may be reached and whereby such incoming signaling impulses may also be utilized for the operation of other local switches to select a desired subscriber's line in the originating exchange if the call is 100 not intended to go beyond this exchange.

Another feature of the invention is the provision of common sender equipments available to toll operators or incoming toll lines and means in connection with the common switching equipments whereby a common sender equipment may be appropriated and used for storing the toll code number of a desired exchange as well as means whereby on the receipt of a signal from 110

the distant exchange over the selected outgoing toll line, said appropriated sender is operated to transmit the toll code number over said toll line.

5 Another feature is the provision, in the sender equipments, of ordinary dialing mechanisms of the type used by operators or subscribers in producing dialing impulses equipped with means for automatic manipulation by incoming impulses to store such impulses and automatic manipulation to transmit impulses.

Another feature of the invention is the provision of cord circuits for the use of the 15 toll operators by means of which both high frequency alternating current and direct current dialing impulses may be transmitted simultaneously to an automatic switching equipment taken for use and by means of 20 which high frequency current signals may be transmitted to or received from a selected outgoing toll line for supervisory purposes during the establishing and release of the toll line connections.

25 Another feature of the invention is the provision of means whereby the direct current impulses representing a toll code number received from a cord circuit of the above type may be utilized for the selecting operations of an idle outgoing toll line and for simultaneously actuating the associated sender to store the toll code number thereon.

Another feature of the invention is the provision of means, in connection with the 35 automatic switching equipment and the sender taken for use, for manipulating the sender to release the toll code number stored thereon; for translating the released direct current impulses constituting said number 40 into high frequency alternating current impulses, and transmitting said impulses over a selected idle outgoing toll line.

Another feature of the invention is the provision of means in connection with an 45 automatic switching equipment and sender taken for use for translating high frequency alternating current signaling impulses received over an incoming toll line into direct current impulses; and means for utilizing said direct current impulses for actuating the automatic switching equipment to select a desired idle outgoing toll line and simultaneously store the direct current impulses on the sender or in case the incoming high frequency alternating current impulses are 55 intended for selection of a subscriber's line in this exchange to translate these impulses into direct current impulses and to utilize the direct current impulses for selectively operating the local switches to connect the 60 incoming toll line with the desired subscriber's line.

This invention has been illustrated by means of the accompanying drawings in which:

Fig. 1 shows a toll operator's cord circuit equipped in accordance with this invention and a jack with an associated line switch by means of which a toll operator may be automatically connected to any one of a plurality of common switching equipments provided for extending a toll connection. 70

Fig. 2 shows a portion of one of said common switching equipments for extending a toll connection. 75

Fig. 3 shows another portion of the common switching equipment for the reception and translation of high frequency alternating current impulses into direct current impulses. 80

Fig. 4 shows a line switch used as a sender selector associated with each common switching equipment for selecting an idle sender equipment. A portion of one of these common sender equipments is also shown in this figure, that is, equipment is shown for the reception of three digit numbers although it should be understood that senders of this type may be arranged for the reception of numbers containing a larger number of digits. 85

Fig. 5 shows another portion of the common switching equipment in which the first selector used in the extension of a toll connection has been shown in detail. Other switches which may be of the same type have been shown diagrammatically, it being understood that regardless of the number of the selectors that are to be employed, they are all identical in their operation with this first selector shown in detail. A portion of the terminal banks of the last selector have been shown to illustrate the grouping of the toll lines. 95

Fig. 6 shows a portion of a standard local switching equipment used in systems of this type for extending automatic connections to subscribers in the same exchange.

Fig. 7 shows a line switching equipment by means of which an incoming toll line 110 may be connected through an automatic switching equipment to a toll line leading to another exchange or to a local subscriber.

Fig. 8 shows three exchanges with the principal elements of the invention indicated schematically, particular attention being given to the arrangement of the toll lines and the routing of the various through connections that may be made by the use of this invention. 115

Fig. 9 illustrates how the various sheets may be assembled in reading the circuits.

General description.

Referring now to the drawings, the method of establishing toll connections in general may be outlined as follows: A subscriber 10 may, by means well known in the art of toll line service, communicate to a toll operator at TO through intermediate 120

operators or by automatic equipment, the number of the wanted subscriber and the exchange at which he is located, and in accordance with the general practice, the subscriber is asked to hang up his receiver until the desired connection has been established at which time the toll operator again communicates with the calling subscriber by inserting plug 12 of a cord circuit 13 into jack 11 and by calling the calling subscriber either automatically or manually as the case may be and thus connecting the last link in the toll line connection.

In establishing a connection to the wanted subscriber, the toll operator refers to the toll code number which has been assigned to the exchange in which the wanted subscriber is located and dials this number, and upon the receipt of a signal indicating that the wanted exchange has been reached, she dials the wanted subscriber's number in that exchange. The first step in establishing a toll connection on the part of the toll operator at TO, is to insert plug 14 of cord circuit 13 into a jack such as 15, it being understood that the operator is provided with a number of cord circuits such as 13 and has access to a number of jacks such as 15 in a regular switchboard as is well known in the art. Jack 15 is associated with the brushes of an automatic switch 16 of the line switch type, the terminals of which are associated with a number of automatic switching equipments such as that shown in Figs. 2, 3, 4 and 5 and the line switch 16 is so arranged as to automatically connect with an idle equipment of this type the moment plug 14 is inserted in jack 15. As soon as a switching equipment has been appropriated various operations take place to actuate the sender selector switch 410 of the same type as line switch 16 to find an idle sender equipment such as is shown at 410. It should be understood that a number of such equipments and senders may be provided for the use of a number of toll operators, that is, a group of senders are common to a larger group of switching equipments which in turn are common to a still larger group of jacks provided for a smaller number of operators. When a sender has been appropriated, operations take place in the switching equipment to cause an impulse to be transmitted over the sleeve lead to actuate a signal in the cord circuit 13 which serves as an indication to the toll operator that dialing of the toll code number may begin.

The operator, who in the meantime has associated her common dialing equipment 17 to the cord circuit 13 by the operation of a dialing key 19 now proceeds to dial the toll code number by operating dial 18. This common dialing equipment 17 is arranged to produce two types of dialing

pulses simultaneously such as direct current impulses alternating with high frequency alternating current. The frequency chosen in this instance for the alternating current impulses is 1000 cycles per second, but it should be understood that alternating current of other high frequencies may be used for these impulses as well as for any other high frequency alternating currents specifically mentioned hereinafter. At this time, the 1000 cycle impulses have no effect in the establishing of a connection whereas the direct current impulses perform two distinct functions, one of these functions being to operate the sender 411 to store, as it were, thereon the toll code number, that is, the sender which includes a number of mechanically operated dials such as 412, 413 and 415 of the standard type used for manual operations is arranged so that each dial will be operated a number of steps equal to the number of pulses in a corresponding digit of the toll code number. The other function consists in operating a series of toll line selectors such as 505 which is shown in detail and others such as 506 and 507 shown diagrammatically but which may also be equipped to operate in response to the impulses in exactly the same manner as selector 505. When a desired toll line, which is to form the first link in a toll line connection has been found by the final selector 507, a signal is automatically transmitted to the opposite end of the selected toll line terminating in a second exchange. This signal which is in the form of a 1000 cycle alternating current interrupted at a 40 cycle rate, causes operations to take place to associate an idle automatic switching and sender equipment in the second exchange identical to that shown in Figs. 2, 3, 4, and 5 with the selected toll line. In other words, this impulse causes actions similar to the actions produced by the insertion of plug 14 in jack 15 to take place, but it should be remembered that this signal is in the form of a high frequency alternating current and when it is received at the second exchange it is caused to operate an alternating current responsive relay which is associated with a line switch such as 710, and this switch is in turn caused to hunt for a connection with an idle switching equipment which in its turn actuates a line switch such as 410 to hunt for and connect with an idle sender such as 411. As soon as an idle sender has been found, actions take place in these equipments at the second exchange to produce and transmit back to the originating exchange another signal. This signal, which is in the form of a 700 cycle alternating current interrupted at a 20 cycle rate is received through the equipment shown in Fig. 3 to cause operations to take place resulting in

the release of the dials 412, 413 and 414 in succession. Direct current impulses representing the digits of the toll code number are now produced by this release of the 5 dials and caused to operate equipment associated with the sender to transmit corresponding high frequency alternating current impulses over the seized toll line. These impulses are in the form of 1000 cycle 10 alternating current pulses transmitted at the dialing rate.

When these high frequency alternating current impulses are received at the second exchange they are in turn received at an 15 equipment identical to that shown in Fig. 3 and cause actions to take place which will result in the operation of the associated sender at this exchange to store the toll code number and at the same time actuate selector switches identical with the selector switches 505, 506 and 507 in this exchange 20 to select an idle toll line leading to a third exchange. This toll line then forms a second link in the connection to the desired 25 exchange.

If the route selected involves connections through a number of other intermediate exchanges and toll lines, the operations just described are repeated; that is, the impulses 30 received at succeeding exchanges seize idle equipments thereat and 700 cycle alternating current impulses interrupted at a 20 cycle rate are sent back to preceding exchanges and the toll code number is stored 35 and re-transmitted to actuate selectors in the same manner as when but a single intermediate exchange is involved.

When finally the desired exchange is 40 reached, the toll line selectors at this exchange are operated in the same manner but instead of selecting an idle toll line leading to an exchange beyond, they are operated so that the final selector 507 will have its brushes establish contact with terminals indicating that this is the final 45 exchange, that is, a ground is connected at these terminals which causes the switch equipment at this exchange to function as follows: First: to release the toll line 50 selectors and disconnect them from the switching equipment. Second: to release the sender at this exchange and cause the toll line code number stored therein to be dissipated without having any effect. 55 Third: to send a high frequency alternating current signal back to the cord circuit at the originating exchange, and fourth: to cause the first of a series of selector switches 60 at this exchange having access to the wanted subscriber's line to be associated with the switching equipment. The signal sent back to the cord circuit is in the form of a 700 cycle alternating current interrupted at a 40 cycle rate and causes the supervisory lamp 65 40 to become illuminated as an indication

to the toll operator that the dialing of the wanted subscriber's number in this exchange may begin.

When the toll operator receives this signal indication she immediately operates her dial 18 in accordance with the local number 70 of the subscriber's line desired and in this instance only the 1000 cycle alternating current impulses are effective over the established toll line connection. The first operation of the dial at this time causes the signal lamp which was lighted as a dialing signal, to be extinguished. These 1000 cycle alternating current impulses are received in an equipment at the terminating exchange 75 identical with that shown in Fig. 3, and cause operations to take place through the line switch 610 to cause switches such as 611, 612 and 613 to select the desired subscriber's line at 615. The operation of these 80 switches forms no part of this invention as their operation is well known in the art and only a sufficient portion thereof has been shown to indicate how the selection may be 85 made and how they react in response to the dialing impulses as far as such reaction 90 may affect the operation of the switching equipments of this invention.

When the subscriber's line at 615 is 95 reached, the toll operator is notified by the lighting of the supervisory lamp 40 and the operator may now proceed to ring the wanted subscriber by operating a ringing key 20 and when the wanted subscriber answers by 100 removing his receiver from the hook, the supervisory signal at the cord circuit is again extinguished to indicate this fact to the operator who now proceeds to set up a connection to the calling subscriber. This 105 may be done as hereinbefore mentioned, manually or automatically. If the connection is set up automatically the cord circuit is manipulated so that the actuation of dial 18 establishes the connection. Conversation between the subscribers may now 110 take place and when it is ended, the toll connection may be released by the operator removing the plugs 12 and 14 from the corresponding jacks and operation will then 115 take place to return all parts of the apparatus to normal as will be more fully described hereinafter.

The advantage of having the toll operators simply dial the complete toll code 120 number at one time without having to pay any attention whatsoever to any supervisory signals during the setting up of a toll connection is readily apparent, but, in addition to this, it is also of considerable 125 advantage and importance, as shown by this invention, to reduce the time of setting up toll connections. It is well known that if the toll operator under the present practice finds, in connections extending through several exchanges, all the toll lines between 130

any two intermediate exchanges busy, the attempt to complete the connection over that route has to be temporarily abandoned, and a second attempt made later over the 5 same route or over another route. This causes considerable delay and intermediate toll lines are unnecessarily tied up in such unsuccessful attempt to complete connections. This invention eliminates, to a considerable extent, these disadvantages as the 10 wiring of the terminal banks at the selectors 505, 506 and 507 at the various exchanges may be such that several routes may be automatically selected for extending 15 connections to a desired exchange. The first idle route may, therefore, be instantly selected and the time of completing a connection reduced to a minimum. The 20 description of wiring scheme and arrangement of the contact banks employed to accomplish these results may, for the sake of clearness, be confined to a description of the arrangement at the selector 507, it being understood that the same general 25 scheme may be applied to any one or all of the other selectors as required.

In this case then, it may be assumed 30 that this selector has access to 100 toll lines divided into 10 groups of 10 lines each, each group of lines leading to a different distant exchange. Referring now specifically to Figs. 5 and 8, if connection between 35 two exchanges, such as A and D, may be reached through intermediate exchanges over two different routes, one involving exchange C only and another involving, in addition to exchange C another exchange B, (not shown), the selector 507 in exchange A would first be set to hunt for an 40 idle line in the group of lines leading to exchange C marked "First group" and if all of the lines in this preferred group are busy, the selector would automatically continue to hunt over the lines leading to exchange B marked "Second group". If the 45 first route is selected, a connection will, of course, extend directly through the exchange C to exchange D, whereas in the second case, a connection will extend through exchanges 50 B and C. This arrangement could, naturally, be varied to suit different conditions and locations of exchanges, and the groups of lines leading to the various exchanges need not be of the same number nor need the 55 routes be confined to but two. It is also understood that a choice of route may also be made at each exchange in accordance with this scheme of wiring by applying it to the terminal banks of the toll line selectors 505, 506 in the same manner it has been shown applied to the terminal banks of selector 507.

Detailed Description.

60 In describing this invention in detail,

it may be of advantage to give a detailed description of the functions involved in setting up a toll connection and completing a call between a subscriber in one exchange, such as A, and a subscriber in a distant 70 exchange, such as D, involving a through toll connection, that is, a connection leading through an intermediate exchange, such as B. This type of connection will now be described in connection with the equipments 75 shown in Figs. 1 to 7 which represents the necessary equipment at one exchange and it should be understood that the equipments at the intermediate exchange B and the terminating exchange D are identical 80 with that at the originating exchange A. Assuming then that the operator at position TO as hereinbefore described has received the wanted subscriber's number from the subscriber at 10 and has inserted plug 14 85 in jack 15, the following circuit is completed: battery, winding of marginal relay 21, left hand winding of relay 22, make-before-break contacts of relay 23, sleeve contacts of plug 14 and jack 15, make- 90 before-break contacts of relay 24 and winding of relay 25 to ground. This circuit causes the energization of relays 22 and 25 the latter relay preparing a circuit for relay 26 as follows: battery, left hand armature 95 and front contact of relay 25, winding of relay 26, to the brush 27 of line switch 16. If line switch 16 is connected to a busy switching equipment, such as is shown in 100 Figs. 2, 3, 4 and 5, the circuit for relay 26 is completed from brush 27 through lead 28 to the left hand armature and front contact of relay 310 to ground, whereupon relay 26 is energized. The energization of relay 26 closes an operating circuit for 105 the driving magnet 29 for the line switch 16 and the brushes of this switch are, therefore, advanced until an idle switching equipment is found, that is, until no ground is 110 found on the terminal engaged by brush 27. At this time, relay 26 deenergizes and magnet 29 is released. Upon the release of relay 26, relay 24 is operated as follows: battery, winding of relay 24, outer right hand armature and back contact of relay 115 26, right hand armature and front contact of relay 25 to ground. The operation of relay 24 closes an obvious circuit for relay 30 which connects the tip and ring conductors from jack 15 through to brushes 120 31 and 32 of the switch 16 to conductors 33 and 34 associated with the portion of the idle switching equipment shown in Fig. 2. The operation of relay 24 also opens the make-before-break contacts of the sleeve circuit to relay 25 which relay is thereby released and connects the sleeve circuit at its outer right hand armature and front contact to the brush 35 of the line switch 125 16 which brush is now connected to lead 130

36 extending to relay 210. A circuit is, therefore, closed from battery at relay 21 through the sleeve lead, winding of relay 210 to ground, causing this relay to operate.

5 The operation of relay 210 closes a circuit for relay 310 as follows: battery, outer right hand armature and front contact of relay 210, conductor 311, winding of relay 310 to ground. The operation of relay 310

10 provides a busy ground for lead 28 so that this switching equipment cannot be taken by any other line switch, such as 16. The operation of relay 210 also closes a circuit at its outer left hand armature and front contact for relays 212 and 213, as follows: battery, winding of relay 213 and left hand winding of relay 212 in parallel to the outer left hand armature and front contact of relay 210 to ground. Relay 212

15 provides a locking circuit for itself as follows: battery, right hand winding of relay 212, inner right hand armature and front contact of this relay, armature and front contact of relay 213 to ground. The

20 purpose of the operation of these two relays will become apparent as the description proceeds. The operation of relay 210 also closes a circuit through a resistance 214 in a connection from lead 36, through the

25 inner right hand armature and front contact of relay 210 to conductor 415. Relay 210 also at its inner left hand armature and front contact closes a connection from ground through its own windings, to lead 312 and resistance 313. The purpose of these connections will be apparent as the description proceeds. If, now, the sender selector 410 is resting on the terminals of a busy sender 411, relay 215 will operate

30 as follows: battery, outer right hand armature and front contact of relay 210, outer left hand armature and back contact of relay 216, outer left hand armature and back contact of relay 217, winding of relay

35 215, conductor 416, middle armature and back contact of relay 417, brush 418 of line switch 410, right hand armature and front contact of relay 419 to ground. The operation of relay 215 completes a circuit for

40 motor magnet 420 of the line switch 410 over the following circuit: battery, left hand armature and front contact of relay 215, conductor 421, winding of magnet 420, through its interrupting contacts to ground, causing this magnet to operate the line switch 410 to advance its brushes to the terminals of an idle sender. When an idle sender is reached, the ground for brush

45 418 is removed and relay 215 is released, causing the motor magnet 420 to stop. Simultaneously with the operation of relay 215, relay 218 is also operated from battery at the outer right hand armature and front contact of relay 210 so that upon the release

50 of relay 215, a circuit is completed for

55 relays 422 and 417 as follows: battery, windings of these relays in parallel, through conductor 423, right hand armature and back contact of relay 215, armature and front contact of relay 218 to ground, causing these relays 422 and 417 to operate. Relay 422 completes at its armatures and front contacts, a connection between conductors 424 and 425 through brushes 426

60 and 427 and left hand windings of repeating coil 428 to battery and ground through the windings of relay 429.

65 It will be noted that an idle sender such as 411 is now associated, through the switching equipment shown in Fig. 2, with the operator's cord circuit 15. The operator may, in the meantime, operate her dialing key 19 to the position marked "Toll" preparatory to dialing. At the lower contacts of this key, a ground is connected to provide an obvious operating circuit for relays

70 23 and 37. These relays operate and close circuits as follows: relay 23 closes an obvious circuit for relay 38 at its left hand armature and front contact and at its make-before-break contacts opens the sleeve lead to relays 22 and 21 and closes it at the right hand armature and front contact to the marginal relay 39. A circuit is now completed for operating this relay as follows: battery, winding of relay 39, right hand armature and front contact of relay 23, sleeve contacts of plug 14 and jack 15, outer right hand armature and front contact of relay 24, brush 35, conductor 36, resistance 214, inner right hand armature and front contact of relay 210, conductor 415, outer armature and front contact of relay

75 417 to ground. Resistance 214 is such that sufficient current is provided to operate relay 39, which now closes a circuit for lamp 40 as follows: battery, right hand armature and back contact of relay 41, left hand armature and front contact of relay 39, upper contacts of "Toll" dialing key 19, lamp 40, armature and back contact of relay 42, lower closed contacts of listening key 43, to ground. Lamp 40 in lighting indicates to the toll operator that the circuit is now prepared for sending dialing impulses.

80 The operation of relay 37 has in the meantime closed at its upper and lower armatures and front contacts, the following fundamental dialing circuit: battery, upper winding of relay 429, upper right hand winding of repeating coil 428, brush 427 of switch 410, inner armature and front contact of relay 422, conductor 424, inner left hand armature and back contact of relay 216, inner lower armature of relay

85 218, inner lower armature and back contact of relay 219, conductor 33, brush 32, lower armature and front contact of relay 30, ring contacts of jack 15 and plug 14, lower armature and front contact of relay 37,

130

conductor 44, windings of retardation coil 45 in series, armature and front contact of relay 46, conductor 47, upper armature and front contact of relay 37, tip contacts of 5 plug 14 and jack 15, upper armature and front contact of relay 30, brush 31, conductor 34, armature and back contact of relay 219, upper armature and back contact of relay 218, right hand armature and back 10 contact of relay 216, conductor 425, brush 426 of switch 410 lower right hand winding of repeating coil 428 lower winding of relay 429 to ground. This causes the operation of relay 429 which closes an obvious circuit at 15 its armature and front contact to ground for relay 419 and the operation of this relay applies a ground to the terminal associated with brush 418 of switch 410 which is thereby made busy to other line switches 20 searching for an idle sender. It should be noted that the lead from the switching equipment to brush 418 opened at the middle armature and back contact of relay 417 when it operated. The fundamental circuit 25 through retardation coil 45 and relay 429 also extends to pulsing relay 510 of toll line selector 505 from battery, left hand winding of pulsing relay 510, inner lower armature of relay 511 and inner lower armature of relay 220, through the ring and tip conductors and retardation coil 45 as previously traced and then through the winding of relay 221, upper armature and back contact of relay 220, upper armature 30 and back contact of relay 511 and right hand winding of relay 510 to ground. Relays 510 and 221 operate in this circuit; relay 221 closing at its armature and back contact an obvious circuit for relay 222 which 35 in operating closes a locking circuit for itself to ground at the armature and front contact of relay 213, whereas relay 510 closes a circuit for relay 512 as follows: battery, winding of relay 512, armature and front contact of relay 510, third lower armature and back contact of relay 511 to ground. The switching equipment of Figs. 2, 3, 4 and 5 is now ready for the reception 40 of impulses representing the toll code number of the exchange desired and these impulses will, as hereinafter described, perform two functions. First to store the toll code number on the sender 411, and second, to select, by means of switches 505, 506 and 507 a toll line route to the desired exchange. 45 The operator may now move her dial 18 off normal and in so doing, closes a circuit for relay 49 as follows: battery, winding of relay 49, right hand armature and back contact of relay 50, off normal contacts 51 of dial 18 to ground. The operation of relay 49 closes an obvious circuit at its right hand armature and front contact for relay 41. The operation of relay 41, at its right hand 55 armature and back contact opens the energizing circuit for lamp 40 which is now extinguished. The operation of relay 49 causes the fundamental circuit through retardation coil 45 to be closed through the left hand windings of repeating coil 52 at 70 the left hand armature and front contact of relay 49. As the dial 18 returns to normal after having been set to the first digit of the toll code number, it opens for each pulse the energizing circuit for relay 46 at its 75 pulsing contacts 53. This circuit may be traced from battery, pulsing contacts 53, left hand armature and back contact of relay 50, winding of relay 46 to ground. Thus, on each release of relay 46, the fundamental circuit through the retardation coil 45 is opened, and relays 429 and relay 510 are therefore alternately retarded and operated in accordance with the operation of the contact 53. It should also be noted that 80 upon the release of relay 46, the fundamental circuit is closed through the left hand windings of repeating coil 52, the right hand windings of which are connected to a 1000 cycle alternating current source 85 90 54. Thus an impulse of high frequency current is transmitted over the fundamental circuit after each direct current impulse, but these impulses do not perform any useful function at this time. 95

To trace first the storing of the toll code number on the sender 411, the release of relay 429 in response to the operation of the dial 18 has no effect on the circuit completed at its armature and back contact in 100 operating relay 431, as this relay is slow to operate, but it should be noted that at the original operation of relay 429 a circuit was closed not only for relay 419 as previously stated but also for relay 435 and operating magnet 436 of the first dial mechanism 412. Upon the first release therefore of relay 429, relay 435 releases and does not again operate until at the end of the first series of impulses as it is slow to operate but quick to release. However on the first operation of relay 435 an obvious circuit for relay 440 was closed operating this relay which provided a locking circuit for itself from ground at the off-normal contacts 441 on the 105 first step of dial 412 in response to the original operation of stepping magnet 436. Therefore, the release of relay 435 on the first release of relay 429 closes a circuit for relay 443 as follows: battery, winding of relay 443, right hand armature of relay 440, right hand armature and back contact of relay 435 to ground. A locking circuit is also provided for this relay to the grounded off-normal contacts 441. Therefore, relays 443 and 440 are maintained operated and relay 435 released during the setting of dial 412 in response to the impulses representing the first digit in the toll code number. The operating magnet 436 however, responds to 110 115 120 125 130

each operation of relay 429 and causes the dial 412 to take one step for each impulse, that is, its armature is attracted for each impulse and causes stepping pawl 437 to engage the ratchet wheel 438 which is thereby ratcheted one step at a time. Dial 412, therefore, takes a position corresponding to the number of interruptions of the circuit for relay 429 which in turn represents the first digit in the toll code number. Relay 419 is slow to release and is, therefore, maintained operated between impulses. It should be noted that relay 442 was also operated over an obvious circuit when contacts 441 were closed to ground. The purpose of the operation of this relay will become apparent as the description proceeds.

On the return of dial 18 to normal, after the first digit has been sent, relay 49 is released and relay 46 is again energized, causing relay 429 to be energized until the next digit is dialed. This last operation of relay 429 causes the re-operation of relay 435 and magnet 436 the final operation of which thereby advances dial 412 to its final point. The operation of relay 435, on the other hand, closes a circuit at its left hand armature and front contact for relay 444 as follows: battery, winding of relay 444, left hand armature and front contact of relay 435, left hand armature and front contact of relay 443 to ground, causing relay 444 to operate. The operation of this relay opens the pulsing lead at its outer right hand armature and back contact thus releasing relay 435 and magnet 436 and extends this lead at this armature and its front contact to the relay 445 and stepping magnet 446 associated with dial 413 for the preparation of this dial circuit for the reception of impulses representing the second digit of the toll code number. The relays associated with this dial are identical with those associated with dial 412, that is, relays 445, 447, 448, 449 and 450 correspond to relays 435, 440, 443, 444 and 442 respectively. The dial 413 is, therefore, advanced in the same manner as the dial 412. After the operation of dial 18 in accordance with the second digit of the toll code number and when relay 429 is finally energized the pulsing lead from this relay is extended through relay 448 to relay 455 and the stepping magnet 456. The third digit is registered on dial 414 in the same manner and the equipment for this dial is similar to that of the other dial, that is, relays 455, 457, 458 and 459 correspond to relays 435, 440, 443 and 444, respectively, of the equipment associated with dial 412. It should be noted that the equipment for this dial 414 is not equipped with any relay corresponding to relay 442 or 450, as this is represented as being the last dial in the series and no further transfer of the pulsing lead is required. The toll code number is,

in this instance, considered as constituting but three digits. It should be understood that other dials may be provided in between dials 413 and 414, in case toll code numbers containing more digits are to be dialed.

The toll code number is, therefore, now registered on sender 411 and the selection of an idle toll line route leading to the desired exchange will now be described. As stated, this selection will take place simultaneously with the storing of the toll code number on the sender 411 and the pulsing relay 510 is therefore released and operated in accordance with the opening and closing of the fundamental circuit. The first operation of relay 510 closes an operating circuit for relay 512 as hereinbefore described and as relay 512 is slow to release, the first release of relay 510 on the first impulse therefore closes a circuit for the operation of relay 513 and the vertical stepping magnet as follows: battery, winding of stepping magnet 514, winding of relay 513, inner armature and front contact of relay 512, armature and back contact of relay 510 to ground at the third lower armature and back contact of relay 511. Relay 513 is slow to release so that upon subsequent operations of relay 510, in response to the impulses, the vertical stepping magnet only is alternately operated and released and caused to advance the brushes 520 of selector 505 to the first vertical group of trunks represented by the first digit in the toll code number. When all of the impulses have been received, relay 510 is held energized for a sufficient period to permit relay 513 to release. Upon the release of relay 513, the rotary magnet 517 is energized to hunt for an idle trunk in this vertical group. The first operation of rotary stepping magnet 517 is accomplished as follows: On the original energization of relay 513 a circuit was closed for relay 516 as follows: battery, winding of relay 516, off normal contacts 515 which were closed on the first rotary step of the selector, armature and front contact of relay 513 to ground at the outer armature and front contact of relay 512. Therefore, on the release of relay 513, relay 516 is maintained operated from the ground at the third lower armature and back contact of relay 511 as follows: battery, winding of relay 516, off normal contacts 515, armature and back contact of rotary stepping magnet 517, left hand armature and front contact of relay 516 to ground at the third armature and back contact of relay 511. This maintains relay 516 operated and provides, upon release of relay 513, a circuit for rotary stepping magnet 57 as follows: battery, winding of stepping magnet 517, right hand armature and front contact of relay 516, make-before-break contacts of relay 513 to ground at the right

hand armature and front contact of relay 512. Rotary stepping magnet 517 now operates and advances the brushes to the first set of terminals representing the first 5 trunk in the selected group. If this trunk is busy, that is, occupied by another selector switch such as 505, a ground will be present on the lead 521. It should be noted that upon the operation of the rotary stepping 10 magnet 517, the energizing circuit for relay 516 was opened at the armature and back contact of the stepping magnet 517 and upon the subsequent release of relay 516, the circuit for the stepping magnet 517 is 15 opened at the right hand armature and front contact of relay 516. This ground on lead 521 of selector 505 will therefore, complete a new energizing circuit for relay 516 as follows: battery, winding of relay 516, 20 off normal contacts 515, armature and back contact of rotary stepping magnet 517, lower outer armature and back contact of relay 511 to ground on lead 521. The operation of relay 516 will, therefore, again close the 25 energizing circuit for rotary stepping magnet 517 which now advances the brushes 520 to the terminals of the second trunk and this alternate operation of relay 516 and magnet 517 is repeated until an idle trunk 30 is found. When an idle trunk is found, the ground on lead 521 is removed and relay 516 cannot again become energized. Therefore, no circuit for rotary stepping magnet 517 is provided at this time and the selector 35 comes to rest with its brushes 520 on the terminals of an idle trunk leading to a second selector such as 506. The leads of the selector 505 connected to brushes 520 will now be extended to the switching equipment 40 shown in Fig. 2 by the operation of relay 511 over a circuit as follows: battery, winding of relay 516, off normal contacts 515, armature and back contact of rotary stepping magnet 517, winding of relay 511, rotary 45 busy contacts 522 to ground at the outer right hand armature and front contact of relay 232 which it should be remembered is operated at this time. This causes the operation of relay 511 and the conductors are extended as described. It is evident that relay 511 cannot operate until an idle 50 trunk is found as the busy ground in lead 521 will short circuit this relay. The circuit for relay 510 is now opened at the upper armature and back contact and inner lower armature and back contact of relay 511, thereby causing the release of relay 510 and also the release of relay 512. The 55 fundamental circuit over the tip and ring leads will, therefore, be advanced to the pulsing relay in the second selector 503 corresponding to relay 510 and this relay will operate causing the operation of the relay corresponding to relay 512. The operation 60 of relay 511 will also provide a busy ground

for the selected trunk by closing a connection from the ground at relay 232 to lead 521 at its lower outer armature and front contact. This second selector 506 and the third selector 507 which are identical with 70 selector 505 will now operate in the same manner in response to the second and third digits of the toll code number.

Toll call routes.

75

It should be explained here how the various routes for the toll code connection may be chosen. For example, if an idle trunk in the proper group of trunks in the first selector represented by the first digit of the 80 toll code number, is found leading to a second selector beginning the preferred route, no further action takes place in the selector 505. If, on the other hand, no trunks are found idle in this group a second route 85 extending over the second selectors associated with another group of trunks may be selected, and in this case the rotary magnet 517 would continue hunting until an idle trunk is found in this second group. That 90 is to say, these groups of trunks available to the first selector could lead to different groups of second selectors having access to groups of trunks leading to third selectors 95 where the same arrangement could be made in regard to the groups of toll lines leading to exchanges any one of which may constitute the first stopping point in a route towards the terminating exchange. It 100 should, of course, be understood that any combination of routes could be connected up over these selectors to choose from, although if an idle trunk is found in the first group of trunks to which the vertical magnet advanced the selector brushes, this preferred route would naturally be selected. Also, as 105 selectors 506 and 507 are identical in operation to that of selector 505 the function of selecting the various routes available through these selectors will be the same. It 110 is now clear how the last selector would choose an idle toll line in a preferred group of toll lines leading to the next intermediate exchange and only in case all the toll lines in that group are busy, an idle toll line in 115 the next available group will be chosen.

Second exchange.

When an idle toll line leading to a second exchange is found, the bridge across the tip and ring which is maintained by the relay in the third selector corresponding to relay 510 will be opened and thus permit the release of relay 221 in the switching equipment shown in Fig. 2. The release of relay 221 closes a circuit for relay 238 as follows: battery, winding of relay 238, outer right hand armature and back contact of relay 224, right hand armature and front contact of relay 222 to ground at the arma- 120 125 130

ture and back contact of relay 221, causing relay 238 to operate and disconnect the tip and ring leads to the outgoing toll line from the remainder of the circuit and connects them instead to a source of 1000 cycle alternating current interrupted at a 40 cycle rate. The operation of relay 218 also opens an obvious energizing circuit for the slow to release relay 226, thereby permitting this relay to release and disconnect the 1000 cycle current interrupted at a 40 cycle rate from the toll line after a short interval. The release of relay 226 closes an obvious circuit for relay 224 at its right hand armature and back contact, causing relay 224 to operate and open the energizing circuit for relay 218 thus causing this relay to release and relay 226 to become re-operated. Relay 224, however, is maintained operated through a locking circuit from battery, winding of relay 224, inner right hand armature and front contact of relay 224 to ground at the armature and front contact of relay 213.

This pulse of high frequency signaling current causes the line circuit at the incoming toll line to be conditioned for setting a call as will now be described. If, for example, a toll line identical to 525 is chosen by the selector 507, it would lead to another exchange in which a line circuit, such as the one shown in Fig. 7, will be located. The call in connection with the operations through the equipment of this second exchange will be described, by means of the circuit shown in Fig. 7 and any other of the circuits shown in Figs. 2, 3, 4 and 5 which of course represent equipment identical to that located at the second exchange. When, therefore, this first impulse of 1000 cycle current interrupted at a 40 cycle rate is received over the toll line, from the originating office, the special alternating current responsive relay 711 is operated in such a manner as to open and close the energizing circuit to ground at the contacts of this relay for relay 712 at a 40 cycle rate. It should be noted here that relay 711 may be of the type illustrated in the copending application of H. W. O'Neill Serial No. 526,152, filed December 31, 1921. Relay 712 now responds in a similar manner and the alternate operation and release of relay 712 will cause the alternating current relay 713 to energize and remain operated as long as the 1000 cycle current interrupted at the 40 cycle rate remains on the line. The operation of relay 713 provides an obvious short circuit for the energized winding of relay 214 as is well known in the art. The release of relay 714 provides a circuit for relay 715 as follows: battery, winding of relay 715, left hand armature and back contact of relay 716, make-before-break contacts of relay 714 to ground. The operation of relay 715 closes a circuit from ground, at its left hand arm-

ture and front contact to the armature of relay 717. It also closes a circuit for the winding of relay 716 from ground, at the armature and back contact of relay 718, but relay 716 does not operate until relay 714 is again energized when the high frequency impulses on the line cease, at which time it operates in series with relay 715 and these relays lead up to the ground at relay 718. The operation of relay 716 provides an operating circuit for relay 720 as follows: battery, right hand armature and back contact of relay 716, right hand make-before-break contact of relay 721 and winding of relay 720 to ground. In case now that the brushes of line switch 710 rest on the terminals of a busy circuit, such as shown in Fig. 2, in this second exchange ground will be encountered on brush 722. In this case, the operation of relay 720 provides a circuit for relay 723 as follows: battery, left hand armature and front contact of relay 720, winding of relay 723 to ground at brush 722. Relay 723 operates and closes a circuit for stepping magnet 724 as follows: battery, magnet 724, interrupting contacts of this magnet, outer armature and right hand contact of relay 724 to ground, causing the stepping magnet to operate and advance the brushes of relay 710 to the terminals of another circuit, such as shown in Fig. 2. That is, the stepping magnet 724 will advance the switch until relay 723 is released causing the stepping magnet to deenergize. The release of relay 723 will now provide a circuit for relay 721 as follows: battery, left and right hand windings of relay 721, inner right hand armature and back contact of relay 723 to ground at the right hand armature and front contact of relay 720, causing relay 721 to operate. The operation of relay 721 closes a circuit for relay 725 as follows: battery, winding of relay 725, contacts 726 of relay 721 to ground at the right hand armature and front contact of relay 720. The operation of relays 721 and 725 closes the tip and ring leads of the incoming toll line and other leads hereinafter mentioned, through the brushes of switch 710 to a switch equipment such as is shown in Fig. 2.

Under this condition, battery is connected from the right hand armature and front contact of relay 716, through the right hand armature and front contact of relay 721 to brush 727 through the winding of relay 227 to ground, causing the operation of relay 227. The operation of this relay closes a circuit for relay 310 as follows: battery, right hand armature and front contact of relay 227, lead 311, and winding of relay 310 to ground. Relay 310 operates and provides a locking circuit for relay 721 as follows: battery, left hand winding of relay 721, contacts 726 and left hand armature of relay 221, brush 722, lead 28, left hand armature

and front contact of relay 310 to ground. Relay 220, the circuit of which was opened upon the energization of relay 721 is slow in releasing so that it holds the circuit for 5 relays 721 and 725 until relay 227 and relay 310 are operated to furnish a holding ground for these relays. It should be noted also that relay 725 in operating disconnects the alternating current responsive relay 711 10 from the tip and ring of the line.

The operation of relay 227 causes the equipment at this exchange to operate in the same manner as the corresponding equipment at the originating exchange operated 15 when the toll operator inserted plug 14 in jack 15. In other words, this first application of 1000 cycle alternating current interrupted at a 40 cycle rate causes the sender selector 410 to select an idle sender and 20 whereas in the former case, relay 210 started the operations for this purpose relay 227 starts the operation in this case, that is, battery is connected, at its right hand armature and front contact for the operation of a 25 relay, such as 218, to start the sender selector and ground is connected at its left hand armature and front contact to provide a leading ground corresponding to that supplied by relay 213.

When therefore, the sender selector 410 in this exchange has established connection with an idle sender, ground is connected to lead 415 as hereinbefore described causing the operation of relay 219 over the inner 30 right hand armature and back contact of relay 210 which, it should be noted, is not operated in this instance. The operation of relay 219 causes the operation of relay 228 as follows: battery, lower outer armature and front contact of relay 219, winding of relay 228, lead 314, armature and back contact of relay 315 to ground. The operation of relay 228 closes the direct current bridged across the tip and ring of the line 35 connected to the first selector switch 505 in this second exchange and thus causes the operation of the corresponding relay 510 in this selector to prepare this circuit for the reception of the toll code number. The operation of relay 219 also disconnects the local tip and ring leads and connects the incoming tip and ring leads to a 700 cycle alternating current source interrupted at a 40 cycle rate shown at 229 connected to the 45 armatures of relay 230. The operation of relay 219 also opens the operating circuit for relay 230 which releases after a short period of time and in this manner a short impulse of a 700 cycle current interrupted 50 at a 20 cycle rate is transmitted through the equipment shown in Fig. 7 over the toll line such as 525 to the originating exchange. This application of high frequency current causes operations to take place at the originating exchange causing the circuits in send-

er 411 to function to release the dials and transmit over the toll line to the second exchange, impulses of 1000 cycle alternating current representing the toll code number.

Originating exchange.

The operation of the equipment at the originating exchange and the release of sender 411 will now be described. When, therefore, the 700 cycle current, interrupted at a 20 cycle rate, is received at the originating exchange, it passes over a path through the tip and ring leads of selectors 507, 506 and 505 in succession, the armatures controlled by relays 220, 218 and 219 55 to relay 315, through windings of transformer 318, amplifying vacuum tube 319 and rectifying vacuum tube 320 of the circuits shown in Fig. 3, in a manner well known in the art. These rectified pulses of 700 cycle current cause the operation and release of relay 315 at a rate corresponding to the rate of interruptions of the 700 cycle current, that is, at 20 cycles rate. This 60 operation and release of relay 315 causes a 90 20 cycle current to be built up through relay 321 which is designed to operate on this current. The operation of this relay short circuits the winding of relay 322 95 over an obvious circuit, permitting this relay to release. The release of relay 322 closes a circuit for the operation of relay 231 in series with the release magnet 460 of the dial 412 in sender 411 and on which the 100 first digit is stored. The circuit for this relay and magnet is as follows: battery, left hand armature and front contact of relay 444, release magnet 460, armature and front contact of relay 442, brush 461, inner left hand armature and front contact of relay 417, lead 462, winding of relay 231, outer left hand armature and back contact of relay 232, lead 323 to ground at the make-before-break contacts of relay 322. Relay 105 110 231 operates and provides a locking circuit for itself to ground at its left hand armature and front contact and at the same time closes an obvious circuit for relay 232, causing this relay to operate and provide a locking circuit for itself through its inner left hand armature and front contact to ground at relay 213. Magnet 460 is thereupon energized permitting dial 412 to return to normal. During its return to 115 120 normal, the pulsing contacts 463 open and close the circuit through relay 464, permitting it to release once for each impulse in the digit. The circuit for relay 464 may be traced as follows: battery, winding of relay 464, pulsing contacts 463 of the dial 412, pulsing contacts 465 of dial 413 and pulsing contacts 466 of dial 414 to ground. Each release of relay 464 connects the 1000 125 cycle source 467 to the left hand windings of repeating coil 428 causing corresponding 130

induced impulses to be transmitted over the tip and ring leads to the outgoing toll line. When the first dial has returned to normal, the ground on its off normal contacts 441 5 is disconnected, permitting the release of relays 440, 442, 443 and 444. Relay 442 is slow in releasing so that the equipments at the second exchange will differentiate between groups of impulses representing different digits. That is, the second dial 413 10 is not released until sufficient time has been given for the necessary functions to take place at the second exchange. The release of relay 442 transfers the ground from the left hand armature and front contact of relay 231 through its make-before-break contacts to the release magnet 468, by way of the armature and front contact of relay 450. This magnet is now energized, permitting 15 the second dial 413 to restore to normal and cause the transmission to the second exchange of a group of pulses representing the second digit. When the second dial is restored to normal, locking ground for relays 447, 448, 449 and 450 is removed, permitting 20 these relays to release and the ground from relay 231 is then transferred to the release magnet 469 of the last sender 414. Impulses representing the last digit are thus 25 transmitted from dial 414 over the line in a similar manner to the previous digits and when the ground at the off normal contact of dial 414 is removed, relays 457, 458 and 459 are released. The release of relay 459 30 disconnects battery from the operating lead 462 except the battery connected through the winding of relay 470. Relay 231 is sufficiently marginal to release under these conditions and upon releasing closes a circuit 35 for relay 216 as follows: battery, winding of relay 216, inner right hand armature and front contact of relay 232, right hand armature and back contacts of relay 231 to ground, causing relay 216 to operate which 40 now disconnects leads 424 and 425 of the sender selector from the tip and ring leads of the toll line. It also disconnects at its outer left hand armature and back contact the operating lead for relay 218, thus 45 causing the release of relay 218 and consequently relays 422 and 417. It should be noted that relay 470 in the sender was operated the moment relay 231 was operated thus insuring the proper functioning of the 50 circuits associated with the last dial.

The release of the relay 422 causes the release of relay 459 which in turn causes the operation of relay 432 which may take place before the release of relay 419 which is slow 55 in releasing. Relay 431 in turn closes a circuit to ground through its left hand armature and front contact and through the winding of relay 470 which relay is now held up in series with relay 431 but as relay 419 releases, a circuit through the right

hand winding of relay 431 is broken. Relay 431 and relay 470 release but as the left hand winding of relay 431 is marginal and cannot of itself hold relay 431 energized, this cycle of operation is provided to permit 70 relay 431 to hold up sufficiently long after the release of relay 419 to hold switch 410 busy by applying ground to the terminal associated with switch 463 to prevent the switch being taken for use before the relays 75 in sender 411 have operated and completely returned to normal.

Second exchange.

Turning now to the functions at the received exchange resulting from the receipt of the 1000 cycle current interrupted at the dialing rate representing the toll code number, it should be noted that these impulses were transmitted from the secondary of repeating coil 428 over leads 424 and 425, the tip and ring leads, through selectors 505, 506 and 507, tip and ring leads of a toll line identical with 525, through the equipment shown in Fig. 7, over the tip and ring brushes of switch 710 to leads 316 and 317, repeating coil 318 and vacuum tubes 319 and 320, to relay 315 in the second exchange. Relay 315 operates in accordance with these amplified and rectified impulses and disconnects the ground from the winding of relay 228 for a period equal to the duration of each pulse received. Each time relay 328 is released, the direct current path across the tip and ring leads is opened. In this manner 95 pulsing relay 510 is alternately released and selector switch 505 caused to operate in the manner as hereinbefore described in response to the first digit and switches 506 and 507 are similarly operated in response to the succeeding digits. Thus, these switches are caused to select and connect to a toll line in a group of toll lines leading to a distant exchange which may be the terminating exchange, that is, the exchange in which the wanted subscriber's line is located. At the same time as the selection for a toll connection is being made, sender 411 at the second exchange is conditioned for repeating 100 the same toll code number to the third exchange, that is, dials 412, 413 and 414 are set to the digits of the toll code number. Now then, if an idle toll line leading to the terminating exchange is found through switches 505, 506 and 507, relay 221 is released and the equipment at the second exchange, due to battery and ground being removed from the tip and ring of the toll line leading to the terminating exchange is also released. The release of this relay closes 115 a circuit as has been previously described causing the operation of relay 218. The operation of this relay connects the tip and ring leads of the outgoing line to the 100 cycle current source at 225 which is interrupted at 120 125 130

a 40 cycle rate until relay 226 is released. The release of relay 226 closes an operating circuit for relay 224 which, in operating, provides a locking circuit for itself through the inner right hand armature and front contact to the ground at relay 213. The effect of this application of 1000 cycle current interrupted at a 40 cycle rate at the terminating exchange, is for the purpose of conditioning this exchange for the reception of the toll code number as hereinbefore described. The equipment at the terminating exchange being identical to that shown in Figs. 2, 3, 4 and 5 consequently selects an idle sender in the same manner as was the idle sender in the originating and the second exchanges. When this condition at the terminating exchange is established, 700 cycle current interrupted at a 20 cycle rate is transmitted over the toll line from the terminating office to the second office, the same as hereinbefore described in connection with the seizing of the equipment at the second office. The effect of these impulses in the second exchange is the operation of relay 321 and the release of relay 322. The release of relay 322 connects ground to lead 323, causing the operation of relay 231. Relay 231 provides a locking circuit for itself to ground at the left hand armature and front contact, and the circuit for relay 231 also, as hereinbefore described, operates the release magnet 460 of the first dial 412 and the succeeding dials 413 and 414 operate so that the toll code number is now transmitted over the toll line from sender 411 to the terminating exchange in the form of 1000 cycle current impulses representing the toll code number. When all the digits have been transmitted, the release of relay 459 causes the disconnection of battery from lead 462 causing the release of relay 231. The release of this relay causes the operation of relay 216 as hereinbefore described, disconnecting leads 424 and 425 of the sender 411 from the tip and ring leads in the toll line leading to the terminating exchange.

Terminating exchange.

The operation of the equipment at the terminating exchange is identical with the operations hereinbefore described in connection with the seizing of an idle sender and the extension of connections through switches 505, 506 and 507 in the originating and second exchanges, that is, the functions are identical up to a certain point. The impulses representing the toll code number which are received and stored in sender 411 of this exchange and the extension of the connection through the switches are identical except that the last switch 507 instead of finding an idle toll line leading to another exchange finds a set of terminals which represent the terminating office. When the brushes of switch 507 find these terminals, the bridge across the tip and ring leads is opened through the selectors, permitting the release of relay 221 in this terminating exchange as above described, 70 causing the operation of relay 238 and the transmission of a short impulse of 1000 cycle current interrupted at a 40 cycle rate. This impulse, however, performs no useful function at this time. Upon connecting 75 these terminals with switch 507 representing the terminating office, a ground is found on one of the terminals, namely 526, and connected to lead 525 which is extended through switches 507, 506 and 505 by the 80 second lower armature and front contact of the operated relay 511, conductor 236, winding of relay 217 in the terminating exchange and through the right hand winding of relay 235 to battery. Relays 217 and 85 235 operate. Relay 235, in operating, connects the 700 cycle alternating current source interrupted at the 40 cycle rate to the toll lines leading to the originating office, but this impulse is too short to cause 90 any operating at the originating office. On the other hand, the operation of the marginal relay 217, opens the circuit for relay 218 at its outer left-hand armature and back contact, causing this relay to release 95 which results in the release of the sender selector 410 and the returning of the sender 411 to normal as hereinbefore described. The release of the relays and dials in sender 411 disconnects ground from lead 415 and 100 opens the other leads from the equipment in Fig. 2 to the sender 411 in the terminating exchange as before described. The release of relay 429 in sender 411 causes the operation of relay 431. The operation of this 105 relay connects a ground at its right hand armature and front contact to the terminal on which brush 418 is resting to hold sender 410 in this terminating exchange busy for the time being after relay 419 is released. 110 Relay 431 provides a locking circuit for itself from ground to the first release magnet 460 and this causes the first release magnet to be energized and permits the first dial to restore to normal as described except that 115 in this instance, the energizing circuit for the magnet is provided from ground at the left hand winding of relay 431, whereas in the previous cases, the release of the senders at the originating and second exchange was 120 provided from a ground on lead 462 from relay 231. The remaining dials are caused to release in succession and when relay 459 is released and battery removed from the circuit for the release magnet, the locking 125 circuit for relay 431 is opened as the left hand winding is marginal and relay 431 is only held up from direct battery after relay 419 is released. This relay 431 in releasing removed ground from the terminal associ- 130

ated with brush 418, leaving this sender accessible for other calls. As relay 422 is released, during the operation of the sender, the toll code number transmitted by the 5 sender has no effect on any of the circuits.

The operation of relay 217 closes a connection for conductor 237 associated with the local switches represented diagrammatically in Fig. 6, from ground at the make- 10 before-break contacts of relay 239. It also closes a circuit for relay 239 as follows: battery, winding of relay 239, outer lower armature and back contact of relay 220, middle left hand armature and front contact 15 of relay 217 to ground, causing relay 239 to operate and disconnect conductor 237 from ground at its make-before-break contact and connecting this conductor instead to the ground at relay 315 over conductor 20 314. It should be noted that switches 505, 506 and 507 in the terminating exchange are now returned to normal by the operation 25 of relay 217 at this exchange, that is, relay 232, it will be noted, is energized and locked to the ground at relay 213. Therefore, a ground is provided for lead 239 to hold relay 511 operated and when relay 217 operates this ground is removed, causing 30 relays 511 to release. The release of relays 511 in selectors 505, 506 and 507 causes the operation of release magnets 526 which consequently returns the switches to normal.

Local selection in terminating exchange.

When, therefore, these selectors have been returned to normal the circuit completed through the armature and front contact of relay 239 causes operations to take place in the local switching equipment shown in 40 Fig. 6 to condition this equipment for the reception of impulses representing the wanted subscriber in this exchange. It will be noted that the ground connected to conductor 237 causes the operation of relay 45 606 associated with the local switching equipment. The circuit for this relay is as follows: battery, winding of relay 606, armature and back contact of relay 607, lead 237, inner right hand armature and front 50 contact of relay 217, armature and front contact of relay 239, lead 314, armature and back contact of relay 315 to ground. Relay 606 causes slow to release relay 608 to operate which in turn establishes an obvious 55 energizing circuit for relay 605. At its inner right hand armature, relay 605 establishes a circuit for relay 607 which may be traced from battery through the winding of relay 607, to ground over the front contact 60 of relay 605. Relay 607 in attracting its right hand armature opens the original energizing circuit for relay 606 which relay thereupon releases, removing the ground from 65 winding of relay 608 which, however,

remains operated in a circuit extended from battery through the winding of relay 608, front contact and right hand armature of relay 607 to ground at relay 315. At its outer left hand armature, relay 605 prepares a circuit for relay 614 and at its inner left hand armature prepares a circuit for relays 622 and 616. At its outer right hand armature, relay 605 causes the start magnet 602 to operate in a circuit extending from 70 battery through the winding of relay 604, back contact and outer right hand armature of relay 614, back contact and armature of relay 616 to ground over the front contact and outer right hand armature of relay 605. Relay 604 causes the rotary magnet 618 to operate in an obvious circuit. The rotary magnet 618 in operating causes the line switch 609 to start hunting for an 75 idle district switch in a manner well known 80 in the art.

When an idle district switch, such as is diagrammatically indicated at 611 is reached, the idle condition thereof being designated by the presence of battery on the test terminal thereof, relay 622 operates in a circuit 85 extending from battery, contacts of sequence switch spring 640, contacts of relay 625 and wiper 621 of line switch 609, front contact and inner left hand armature of 90 relay 605, both windings of relay 622 to ground through the winding of relay 616. Relay 662, in attracting its armature, short circuits its own right hand winding thereby reducing the resistance in the circuit 95 just traced sufficiently to permit marginal relay 616 to operate in series with relay 622. Relay 616, upon energizing, causes cut off relay 614 to energize in a circuit 100 extending from battery through the winding of cut off relay 614, front contact and armature of relay 616 to ground over the front contact and outer right hand armature of relay 605.

Relay 614, in attracting its outer right 105 hand armature, opens the energizing circuit for relay 604 whereupon this magnet restores, causing rotary magnet 618 to release. In attracting its middle left hand armature, relay 614 locks up under the control of relay 605, and at its inner right hand and outer left hand armatures and front contacts closes through the tip and ring leads to corresponding terminals of switch 611 for purposes hereinafter to be set 110 forth. At its inner left hand armature, relay 614 causes relay 625 to operate in a circuit extending from battery, through the winding of relay 625, wiper 641 of line switch 609 to ground through the inner left 115 hand armature and front contact of relay 614. Relay 625, in attracting its armature removes battery from the test brush 621 of line switch 609, whereupon relays 616 and 622 release, the former opening the 120 125 130

original energizing circuit for relay 614 which, however, remains locked up to ground at its own middle left hand armature and front contact.

- 5 The operation of the control relay 625 of the selected district switch causes an idle sender to be selected in the well known manner whereupon relay 600 operates causing relay 601 to operate through intermediary 10 relays (not shown) to cause a dialing signal to be given to the toll operator at TO in the following manner. Relay 601, in operating, places a ground on the tip conductor of the line switch 609. This ground 15 causes relay 627 to operate in a circuit extending from battery through the winding of relay 627, inner right hand armature and back contact of relay 628, inner right hand armature and front contact of relay 614, 20 wiper 698 of switch 609, lower left hand contacts of sequence switch spring 680 (1+16), upper right hand contacts of said spring (23/4+10) to ground at the contacts of relay 601. Relay 627, in operating, connects ground to lead 681, causing relay 235 to operate over the following circuit: battery, right hand winding of relay 235, lead 681, armature and front contact of relay 627, to ground at the inner right hand armature and front contact of relay 605. The 25 operation of relay 235 causes the connection of 700 cycle alternating current interrupted at a 40 cycle rate to the tip and ring of the incoming toll line. This high frequency signal is transmitted over the toll lines to the receiving circuit as shown in Fig. 3 at the originating exchange where it is received at the transformer 318 and amplified and rectified to cause the operation 30 of relay 325 in response to the interruptions of the 700 cycle current at the 40 cycle rate. The operation of this relay causes the release of relay 326 which in turn connects ground through resistance 313 and lead 312 to the inner left hand armature and back contact of relay 210, lead 36, brush 35, outer right hand armature and front contact of relay 24, sleeve contacts of jack 15 and plug 14, right hand armature and front contact of relay 23, winding of relay 39 to battery. Relay 39 operates in this circuit and closes a circuit for lamp 40 as follows: battery, right hand armature and back contact of relay 41, left hand armature and front contact of relay 39, upper operating contacts of the toll key 19, lamp 40, armature and back contact of relay 42 to ground at the normally closed contact of listening key 43. The lamp is lighted in this circuit to indicate to the toll operator that the local switching equipment at the terminating exchange is in condition for the reception of the digits representing the wanted subscriber's number. The wanted subscriber's number is now 45 dialed by the operator in the same manner as was described for the dialing of the toll code number. The opening and closing of the direct current bridge across the tip and ring of the outgoing toll line at the armature and contacts of relay 46 perform no function in this instance. The subscriber's number, in this case, is transmitted in the form of pulses of 1000 cycle alternating current from the source at 54 by the operation and release of relay 46, in accordance with the interruptions of pulsing contacts 53 as above explained, that is, each pulse of 1000 cycle current is equal in length to the open period of the pulsing contacts. Thus high frequency current impulses representing the wanted 50 subscriber's number are received at the receiving circuit shown in Fig. 3 at the terminating exchange, causing relay 315 to respond to each impulse. The operation of this relay, therefore, breaks the circuit for pulsing relay 600 in the sender and this relay thus responds to the pulses representing the wanted subscriber's number. When all pulses are registered in the sender, ground on relay 601 is removed from the tip lead thereby causing relay 627 to release which in turn opens the circuit for relay 235. This relay in releasing removes the 700 cycle current interrupted at the 40 cycle rate from the line and relay 39 in the cord circuit is 55 thereby released and lamp 40 extinguished to indicate to the toll operator that the sender is satisfied. The toll operator now restores the dialing key 19 marked "Toll" to normal position, thus releasing relay 23 in opening the connection for lamp 40 through the dialing key and extending the sleeve lead to relays 23 and 21. Relay 38 which is slow to release is, therefore, held operated by the locking circuit provided by the left hand armature and front contact of relay 22 when this relay operates on the release of relay 23. 60 When the called line is reached, a ground will be connected to the contact on which wiper 638 of line switch 609 is resting whereupon relay 628 operates in a circuit which may be traced from battery through the winding of relay 628, inner left hand armature and back contact of relay 628, middle right hand armature and front contact of relay 614, wiper 638 and contacts 660 to ground. Relay 628 locks through its contacts 647 under the control of relay 614. At its inner right hand armature, relay 628 disconnects relay 627 from the tip conductor of the connection and at its inner left hand armature and front contact it connects relay 627 to the wiper 638 of line switch 609. At its outer left hand armature, relay 628 establishes a circuit for relay 220 which may be traced from battery through the winding of relay 220, make-before-break contacts of relay 220, conductor 683, front contact and outer left hand armature of relay 628, to 65 70 75 80 85 90 95 100 105 110 115 120 125 130

ground through the front contact and inner right hand armature of relay 605. Relay 220 locks up to conductor 684 to ground independent of the connection through the 5 contacts of relay 628. Relay 671 also operates in parallel with relay 220 as a result of the operation of relay 628 and the circuit for this relay is obvious. Relay 671 in attracting its left hand armature locks to ground at the inner right hand armature of relay 605, thereby removing itself from the control of relay 628. At its inner right hand armature, relay 671 prepares a circuit for ringing relay 699 as will hereinafter appear.

If the called line is idle, a steady ground will be connected to contact 660 and relay 627 will operate over a path including battery, winding of relay 627, front contact 20 and inner left hand armature of relay 628, middle right hand armature and front contact of relay 614, wiper 638, to ground at 660. Relay 627, in operating, causes the operation of relay 325 over a circuit as 25 previously traced which as before explained connects current from the 700 cycle source interrupted at the 40 cycle rate to release relay 325 in the receiving circuit at the originating exchange and the connection of 30 ground to the lead 312 by the release of relay 326 causes the operation of lamp 40 by reducing the resistance in the sleeve lead permitting the operation of the marginal relay 21. Relay 21, in operating, closes a 35 circuit for lamp 40 as follows: battery, armature and back contact of relay 21, lamp 40, armature and back contact of relay 42, ground at the closed contacts of listening key 43. The lighting of lamp 40 at this 40 time indicates to the operator that the subscriber's line is idle and that ringing signals may be transmitted to the subscriber. To this end, the toll operator actuates the 45 ringing key 20 and thereby connects to the line the source of 1000 cycle current interrupted at a 20 cycle rate which is associated with the contacts of relay 38. This ringing signal is received at the receiving equipment shown in Fig. 3 at the terminating exchange, causing the operation of relay 321 50 and the release of relay 322 connecting ground to conductor 323 which causes the operation of ringing relay 699 associated with selector 611. The circuit for this relay may be traced as follows: battery, winding of relay 699, sequence switch contact 694, brush 697, right hand armature and front contact of relay 671, conductors 685 55 and 323 to ground at relay 322. The operation of relay 699 connects ringing current and ground from source 692, as is well known in the art, to call the wanted subscriber at 615. When the called subscriber, in response to this signal removes the receiver from the hook, ground is removed

from contact 660 of switch 611, thereby interrupting the previously traced circuit for relay 627. Relay 627 thereupon releases thus opening the circuit for relay 235, removing the signal from the 700 cycle current source interrupted at a 40 cycle rate from the line, and causing lamp 40 to be extinguished, indicating to the operator that the subscriber has answered. In case the switchhook of the called subscriber is moved 70 up and down at any time during the connection, lamp 40 will alternately be lighted and extinguished; that is, when the receiver is on the hook the lamp will light and when the receiver is off the hook the lamp will be 75 extinguished. This would indicate to the toll operator that the calling subscriber desires her attention. As the connection to the called subscriber is now completed, the toll operator, as hereinbefore stated, may 80 call the calling subscriber and, as soon as the calling subscriber responds, conversation may take place.

Attention will now be given to the equipment provided for indicating busy conditions during the setting up of a toll line connection. In case, for example, all trunks or toll lines leading to a particular group or groups of selectors such as 506 and 507 are busy, a signal is transmitted back to 90 the toll operator causing lamp 40 to be flashed at a certain rate per minute, for example, at a 60 cycle rate, whereas in case the called subscriber's line was busy, the lamp 40 will be flashed at a different rate, 100 for example, at a 120 cycle rate. In the former case, the selectors 505, 506 and 507 will advance over the busy trunk terminals or toll line terminals and as the last set of terminals have been passed, contacts 522 105 will be operated. This closes a circuit for relay 235 as follows: battery, left hand winding of relay 235, right hand winding of relay 217, conductor 236, second lower armature and front contact of relay 511, 110 or the corresponding contacts of the corresponding relay in switches 506 and 507 to the upper closed contacts of the off normal contacts 522 to ground through an interrupter 530 where the circuit is interrupted 115 at a rate of 60 per minute and relay 235 responds to these impulses whereas relay 217 is not affected. The pulsing of relay 235 causes corresponding impulses of 700 cycle current interrupted at a 40 cycle rate 120 to be transmitted over the line back to the toll operator's position to flash lamp 40 at the corresponding rate in a manner as heretofore described. In case relay 235 is locked in the switching equipment of the 125 originating exchange, this relay will apply a ground at its outer left hand armature and front contact through resistance 214, at the inner right hand armature and front contact of relay 210 and thus reduce the 130

resistance of the sleeve circuit and cause the lamp 40 to be flashed accordingly as heretofore described.

In the latter case, that is, when the subscriber's line is found busy, this busy condition will be indicated by the interrupter 662 being connected through to operate relay 627 at a rate of 120 operations per minute. The circuit for this relay may be traced as follows: battery, winding of relay 627, inner left hand armature and front contact of relay 628, middle right hand armature and front contact of relay 618, brush 638, sequence switch contact 663 through interrupter 662 to ground. The pulsing of relay 627 will open and close the circuit for relay 235 at the corresponding rate over a circuit as previously traced for this relay and cause lamp 40 to flash at a rate of 120 per minute indicating thereby to the operator that the wanted subscriber's line is busy.

To release toll connections after conversation, it is merely necessary for the called subscriber to hang up his receiver which will light lamp 40 as hereinbefore described, steadily and this indicates to the toll operator that the called subscriber desires the connection to be released and the toll operator removes plug 14 from jack 15 and all circuit connections are restored to normal.

In regard to the toll operator's cord circuits, such as 13, it should be understood that they can be used not only in connections as described above, but also for ring down in both directions and automatic connections for associating the cord circuit with a calling subscriber. In case of connections extended on the ring down basis to a called subscriber, the key 19 is not operated and only relays 21, 42 and 48 and lamp 40 are concerned. In this case, the insertion of plug 14 into the outgoing toll line jack will cause the operation of relay 21 but lamp 40 will not be lighted as the circuit completed by relay 21 will operate relay 42 as follows: battery, armature and front contact of relay 21, left hand armature and back contact of relay 38, winding of relay 42, armature and back contact of relay 55 to ground. Relay 48 also receives current from battery at relay 21 over a circuit passing through the right hand armature and back contact of relay 42 to ground at test energy key 43 but is prevented from operating as relay 42 is quicker in responding and consequently opens the current for relay 48. As well known in the art during the progress of the connection an alternating current signal is received for example at the time the wanted subscriber's line is reached. This signal operates the alternating current responsive relay 55 and as a consequence, relay 42 will be released and the circuit for relay 48

closed causing this relay to operate. Lamp 40 will now also operate in a parallel circuit from battery at relay 21 to ground over the circuit completed at the armature and back contact of relay 42 to the ground at 70 the contact of key 43 and the lighting of lamp 40 in this case indicates to the operator that the subscriber's line has been reached and that ringing may commence. The ringing key 20 is, therefore, operated and 75 ringing current from the source 54 is transmitted to the wanted subscriber's telephone circuit. When the ringing key is operated, lamp 40 is extinguished as relay 55 is cut off from the line and relay 42 is again 80 operated from the battery at relay 21 to the ground at the armature and back contact of relay 55 and relays 42 and 48 are now locked up until the listening key is operated.

When the operator is ready to re-establish a connection with a calling subscriber, the calling subscriber may be reached as stated on the ring down basis. The insertion of plug 12 into jack 11 completes the connection to the calling subscriber 10 and relay 56 in operating completes the tip and ring lead to the bridge relay 57 as is well known in the art. This relay 56 operates when the calling subscriber's line is reached and 90 causes a signal 58 to be lighted, indicating that ringing may begin. In ringing a calling subscriber, ringing current is applied by the operation of the left hand portion 59 of the ringing key 20, as is well known in the 100 art.

In case an automatic extension to the calling subscriber is desired, plug 12 is also inserted in a jack corresponding to jack 11 and the dialing key 19 is operated to the 105 position marked "Local". The operation of this dialing key in this manner causes the operation of relay 50 over an obvious circuit and this relay associates the dialing leads with the armatures of relay 60. At the 110 operation of the dial from normal, a circuit will be closed for relay 60 as follows: battery, winding of relay 60, upper closed contacts of dialing key 19, marked "Local", right hand armature and front contact of 115 relay 50, off normal contacts 51 to ground, causing this relay to operate thus completing the connection from the dial 18 to the tip and ring leads of the cord current leading through the plug 12 towards the calling subscriber's line. This circuit may be traced as follows: battery, pulsing contact 53 of dial 18, left hand armature and front contact of relay 50, upper inner armature and front contact of relay 58 to the tip of 120 the line, back through the ring of the line to the lower armature and front contact of relay 59 to ground. On the return of dial 18 to normal, this circuit will be interrupted in accordance with the first digit of the 130

number of the calling subscriber's line and the subsequent operations of the dial in accordance with the following digits will extend the connection to the calling subscriber as is well known in the art.

What is claimed is:

1. In a telephone system, toll lines, a cord circuit including impulse transmitting means, means for selecting toll lines comprising a plurality of automatic switching equipments, a plurality of senders, means operative on the connection of the cord circuit to the toll line selecting means for selecting an idle switching equipment and for selecting and associating therewith an idle sender, means operative in response to impulses from the cord circuit for storing said impulses on the sender and for actuating the switching equipment to select an idle toll line in a group corresponding to the digits represented by said impulses and means responsive to an impulse incoming over said selected toll line for operating the sender to transmit over said toll line impulses of a different character representing said digits.

2. In a telephone system, toll lines, a cord circuit including impulse transmitting means, means for selecting toll lines comprising a plurality of automatic switching equipments, a plurality of senders, means operative on the connection of the cord circuit to the toll line selecting means for selecting an idle switching equipment and for selecting and associating therewith an idle sender, means operative in response to impulses from the cord circuit for storing said impulses on the sender and for actuating the switching equipment to select an idle toll line in a group corresponding to the digits represented by said impulses and means responsive to a high frequency alternating current impulse incoming from said toll line for operating the sender to transmit over said toll line impulses of high frequency alternating current representing said digits.

3. In a telephone system, toll lines, a cord circuit including a direct current transmitting means, means for selecting toll lines comprising a plurality of automatic switching equipments, a plurality of senders, means operative on the connection of the cord circuit to the toll line selecting means for selecting an idle switching equipment and for selecting and associating therewith an idle sender, means operative in response to said direct current impulses from said cord circuit for storing said impulses on the sender and for actuating the switching equipment to select an idle toll line in a group corresponding to the digits represented by said impulses and means responsive to an impulse incoming over said selected toll line for operating the sender

to transmit over said toll line impulses of a different character representing said digits.

4. In a telephone system toll lines, a cord circuit including impulse transmitting means, means for selecting toll lines comprising a plurality of automatic switching equipments, a plurality of senders, means including a switch operative on the connection of the cord circuit to the toll line selecting means for selecting an idle switching equipment, means including a switch operative when an idle switching equipment has been found for selecting and associating therewith an idle sender, means operative in response to impulses from the cord circuit for storing said impulses on the sender and for actuating the switching equipment to select an idle toll line in a group corresponding to the digits represented by said impulses and means responsive to an impulse incoming from said selected toll line for operating the sender to transmit over said toll line impulses of a different character representing said digits.

5. In a telephone system, toll lines, a cord circuit including impulse transmitting means, means for selecting toll lines comprising a plurality of automatic switching equipments, a plurality of senders, means operative on the connection of the cord circuit to the toll line selecting means for selecting an idle switching equipment and for selecting and associating therewith an idle sender, means operative in response to the impulses from the cord circuit for storing said impulses on the sender and for actuating the switching equipment to select an idle toll line in one group of toll lines corresponding to the digits represented by said impulses and for selecting an idle toll line in another group of toll lines corresponding to the digits represented by said impulses if all the toll lines in the first group are busy, and means responsive to an impulse incoming from said selected toll line for operating the sender to transmit over the selected toll line impulses of a different character representing said digits.

6. In a telephone system, toll lines, a cord circuit including current impulse transmitting means and a signal, means for selecting toll lines comprising a plurality of automatic switching equipments, a plurality of senders, means operative on the connection of the cord circuit to the toll line selecting means for selecting an idle switching equipment and for selecting and associating therewith an idle sender, means for operating said signal when an idle sender is associated with the automatic switching equipment, and means operative in response to impulses from the cord circuit for storing said impulses on the sender and for actuating the switching equipment to select an idle toll line in a group corre-

sponding to the digits represented by said impulses.

7. In a telephone system, toll lines, a cord circuit including current impulse transmitting means and a signal, means for selecting toll lines comprising a plurality of automatic switching equipment, a plurality of senders, means operative on the connection of the cord circuit to the toll line selecting means for selecting an idle switching equipment and for selecting and associating therewith an idle sender, means operative in response to impulses from the cord circuit for storing said impulses on the sender and for actuating the switching equipment to select an idle toll line in a group corresponding to the digits represented by said impulses and means for operating said signal if all the toll lines in said group are busy.

8. In a telephone system, toll lines, a cord circuit including current impulse transmitting means and a signal, means for selecting toll lines comprising a plurality of automatic switching equipments, a plurality of senders, means operative on the connection of the cord circuit to the toll line selecting means for selecting an idle switching equipment and for selecting and associating therewith an idle sender means for operating said signal in one characteristic manner when an idle sender is associated with the automatic switching equipment, means operative in response to impulses from the cord circuit for storing said impulses on the sender and for actuating the switching equipment to select an idle toll line in a group corresponding to the digits represented by said impulses and means for operating said signal in a different characteristic manner if all toll lines in said group are busy.

9. In a telephone system, toll lines, a cord circuit including impulse transmitting means, means for selecting toll lines comprising a plurality of automatic switching equipments, a plurality of senders each including a plurality of automatic dialing devices adapted to be set in succession in response to succeeding series of impulses representing digits, means operative on the connection of the cord circuit to the toll line selecting means for selecting an idle switching equipment and for selecting and associating therewith an idle sender, means operative in response to impulses from the cord circuit for storing said impulses on the sender and for actuating the switching equipment to select an idle toll line in a group corresponding to the digits represented by said impulses and means responsive to an impulse incoming from said selected toll line for operating the sender to transmit over said toll line impulses of a different character representing said digits.

10. In a telephone system, toll lines, a cord circuit including current impulse transmitting means, means for selecting toll lines comprising a plurality of automatic switching equipments each including a series of selector switches, a plurality of senders, means operative on the connection of the cord circuit to the toll line selecting means for selecting an idle switching equipment and for selecting and associating therewith an idle sender, means operative in response to impulses from the cord circuit for storing said impulses on the sender and for actuating the switching equipment to select an idle toll line in a group corresponding to the digits represented by said impulses and means responsive to an impulse incoming from said selected toll line for operating the sender to transmit over said toll lines impulses of a different character representing said digits.

11. In a telephone system, toll lines, a cord circuit including impulse transmitting means, means for selecting an idle toll line comprising a plurality of automatic switching equipments, a plurality of senders, means operative on the connection of the cord circuit to the toll line selecting means for selecting an idle switching equipment and for associating therewith an idle sender, means responsive to impulses from said cord circuit for storing said impulses thereon and actuating the switching equipment to select an idle toll line represented thereby and means operated when the toll line has been found for transmitting a current impulse of one character over the toll line, means responsive to an impulse of a different character incoming over the toll line for operating the sender to transmit over said toll line high frequency alternating current impulses corresponding to the impulses stored thereon, and automatic switching means at the opposite end of the selected toll line responsive to said impulses for extending the connection beyond.

12. In a telephone system, toll lines, a cord circuit including impulse transmitting means, means for selecting an idle toll line comprising a plurality of automatic switching equipments a plurality of senders, means operative on the connection of the cord circuit to the toll line selecting means for selecting an idle switching equipment and for associating therewith an idle sender, means responsive to impulses from said cord circuit for storing said impulses thereon and actuating the switching equipment to select an idle line represented thereby, means operative when the toll line has been found for transmitting an impulse of one character over the toll line, means responsive to an impulse of a different character incoming over the toll line for operating the sender to transmit over said toll line high frequen-

cy alternating current impulses corresponding to the impulses stored thereon, and means operative when the high frequency current impulses have been transmitted for disassociating the sender from the automatic switching equipment.

13. In a telephone system, a toll line, a cord circuit including impulse transmitting means, means for selecting a toll line comprising a plurality of automatic switching equipments, a plurality of senders, means operative on the operation of the cord circuit to the toll line selecting means for selecting an idle switching equipment and for selecting and associating therewith an idle sender, means responsive to impulses from said cord circuit for storing said impulses thereon and actuating the switching equipment to select an idle toll line represented thereby, means operative when the toll line has been found for transmitting an impulse consisting of a high frequency alternating current interrupted at a certain rate over the toll line and means responsive to an impulse consisting of a high frequency alternating current of a different frequency interrupted at a certain rate incoming over the toll line for operating the sender to transmit over said toll line high frequency alternating current impulses corresponding to the impulses stored thereon and automatic switching means at the opposite end of the toll line responsive to said last mentioned impulses for extending the connection further.

14. In a telephone system, a first exchange, a second exchange, and other exchanges, toll lines interconnecting said exchanges, a cord circuit including impulse transmitting means at the first exchange for selecting an idle toll line extending to the second exchange comprising a plurality of automatic switching equipments, a plurality of senders, means operative on the connection of the cord circuit to the toll line selecting means for selecting an idle switching equipment and for associating therewith an idle sender, means operative in response to impulses from the cord circuit for storing said impulses on the sender and for actuating the switching equipment to select an idle toll line leading to the second exchange and means operative when a toll line has been found for transmitting an impulse over the toll line to the second exchange, means at the second exchange for selecting a toll line extending to other exchanges comprising a plurality of automatic switching equipments, a plurality of senders, means operative in response to the impulses received from the first exchange for selecting an idle switching equipment and for selecting and associating therewith an idle sender in this second exchange, means operative when a switching equipment and

a sender have been found for transmitting an impulse over the toll line leading to the first exchange, means at the first exchange responsive to the impulses from the second exchange for operating the sender at the first exchange to transmit to the second exchange impulses corresponding to the impulses stored thereon, means at the second exchange responsive to said impulses from the first exchange for storing said impulses on the sender at the second exchange and actuating the associated switching equipment to select an idle toll line extending to another exchange, means at said second exchange operated when the toll line to another exchange has been found for transmitting an impulse to said other exchange, means at the second exchange responsive to an impulse incoming over a toll line leading to the said other exchange for operating the sender at the second exchange to transmit to said other exchange impulses corresponding to the impulses stored thereon and automatic switching means at the opposite end of the toll line leading to the other exchange responsive to the impulses from the second exchange for extending a connection beyond said other exchange.

15. In a telephone system, toll lines, subscriber's lines, a cord circuit, means associated with said cord circuit for transmitting direct and alternating current impulses representing digits, means for selecting toll lines comprising a plurality of automatic switching equipments, a plurality of senders, means operative on the connection of the cord circuit to the toll line selecting means for selecting an idle switching equipment and for selecting and associating therewith an idle sender, means operative in response to the direct current impulses for storing the same on the sender and for actuating the switching equipment to select an idle toll line in the group corresponding to the digits represented by said impulses and means for operating the sender to transmit over the selected toll line alternating current impulses representing said digits, means at the opposite end of the selected toll line for extending it to subscribers' lines comprising means including an automatic switching equipment and a sender responsive to the alternating current impulses from the first mentioned sender to set this last mentioned sender in accordance with the digits represented by said impulses and to set the automatic switching equipment on a terminal representing the digits, automatic switching means, means actuated when said terminal is found for releasing the sender and automatic switching equipment and connecting the toll line with said automatic switching means and means responsive to alternating current impulses received from the impulse transmitting means

- associated with the cord circuit for actuating said automatic switching means to connect the toll line with a subscriber's line corresponding to the digits represented by 5 said alternating current impulses.
16. In a telephone system, toll lines, subscribers' lines, a cord circuit, a signal in said cord circuit, means associated with said cord circuit for transmitting direct and 10 alternating current impulses representing digits, means for selecting toll lines comprising a plurality of automatic switching equipments, a plurality of senders, means operative on the connection of the cord circuit 15 to the toll line selecting means for selecting an idle switching equipment and for selecting and associating therewith an idle sender, means operative in response to the direct current impulses for storing the 20 same on the sender and for actuating the switching equipments to select an idle toll line in a group corresponding to the digits represented by said impulses and means for operating the sender to transmit over the 25 selected toll line alternating current impulses representing said digits, means at the opposite end of the selected toll line for extending it to subscribers' lines comprising means including an automatic switching 30 equipment and a sender responsive to the alternating current impulses from the first mentioned sender to set this last mentioned sender in accordance with the digits represented by said impulses and to set 35 the automatic switching equipment on a terminal representing the digits, automatic switching means, means actuated when said terminal is found for releasing the sender and automatic switching equipment and 40 connecting the toll line with said automatic switching means, means actuated when the toll line is connected with the automatic switching means for operating the signal at the cord circuit to indicate that the 45 selection of a subscriber's line may begin and means responsive to alternating current impulses received from the impulse transmitting means associated with the cord circuit for actuating such automatic switching 50 means to connect the toll line with a subscriber's line corresponding to the digits represented by such alternating current impulses.
17. In a telephone system, toll lines, subscribers' lines, a cord circuit, a signal in said cord circuit, means associated with said cord circuit for transmitting direct and alternating current impulses representing digits, means for selecting toll lines comprising a plurality of automatic switching equipments, a plurality of senders, means operative on the connection of the cord circuit 55 to the toll line selecting means for selecting an idle switching equipment and for selecting and associating therewith an idle sender, means operative in response to the direct current impulses for storing the same on the sender and for actuating the switching equipments to select an idle toll line in a group corresponding to the digits represented by said impulses and means for operating the sender to transmit over the selected toll line alternating current impulses 60 representing said digits, means at the opposite ends of the selected toll line for extending it to subscribers' lines comprising means including an automatic switching equipment and a sender responsive to the alter- 65
- idle sender, means operative in response to the direct current impulses for storing the same on the sender and for actuating the switching equipment to select an idle toll line in a group corresponding to the digits 70 represented by said impulses and means for operating the sender to transmit over the selected toll line alternating current impulses represented by said digits, means at the opposite end of the toll selected line for 75 extending it to the subscribers' lines comprising means including an automatic switching equipment and a sender responsive to the alternating current impulses from the first mentioned sender to set this last mentioned sender in accordance with the digits represented by said impulses and to set the automatic switching equipment on a terminal representing the digits, automatic switching means, means actuated when 80 said terminal is found for releasing the sender and automatic switching equipment and connecting the toll line with said automatic switching means, means actuated when a toll line is connected with the automatic 85 switching means for transmitting an impulse consisting of a high frequency alternating current interrupter at a low frequency rate over the toll line towards the cord circuit, means responsive to alternating current impulses received from the impulse transmitting means associated with the cord circuit for actuating said automatic switching means to connect the toll line with a subscriber's line corresponding to the digits 90 represented by said alternating current impulses and means at the originating end of a toll line and in the cord circuit responsive to said last mentioned impulse for actuating 95 said signal.
18. In a telephone system, toll lines, subscribers' lines, a cord circuit, a signal in said cord circuit, means associated with said cord circuit for transmitting direct and alternating current impulses representing digits, means for selecting toll lines comprising a plurality of automatic switching equipments, a plurality of senders, means operative on the connection of the cord circuit 100 to the toll line selecting means for selecting an idle switching equipment and for selecting and associating therewith an idle sender, means operative in response to the direct current impulses for storing the same on the sender and for actuating the switching equipments to select an idle toll line in a group corresponding to the digits represented by said impulses and means for operating the sender to transmit over the selected toll line alternating current impulses 105 representing said digits, means at the opposite ends of the selected toll line for extending it to subscribers' lines comprising means including an automatic switching equipment and a sender responsive to the alter- 110

- 125
- 130

inating current impulses from the first mentioned sender to set this last mentioned sender in accordance with the digits represented by said impulses and to set the automatic switching equipment on a terminal representing the digits, automatic switching means, means actuated when said terminal is found for releasing the sender and automatic switching equipment and connecting the toll line with said automatic switching means, means actuated when the toll line is connected with the automatic switching means for operating the signal at the cord circuit to indicate that the selection of a subscriber's line may begin, means responsive to alternating current impulses received from the impulse transmitting means associated with the cord circuit for actuating said automatic switching means to connect the toll line with a subscriber's line corresponding to the digits represented by said alternating current impulses and means actuated when the wanted subscriber's line is reached for disabling the signal at the cord circuit.

19. In a telephone system, toll lines, subscribers' lines, a cord circuit, a signal in said cord circuit, means associated with said cord circuit for transmitting direct and alternating current impulses representing digits, means for selecting toll lines comprising a plurality of automatic switching equipments, a plurality of senders, means operative on the connection of the cord circuit to the toll line selecting means for selecting an idle switching equipment and for selecting and associating therewith an idle sender, means operative in response to the direct current impulses for storing the same on the sender and for actuating the switching equipments to select an idle toll line in a group corresponding to the digits represented by said impulses and means for operating the sender to transmit over the selected toll line alternating current impulses representing said digits, means at the opposite ends of the toll line for extending the toll line to subscribers' lines comprising means including an automatic switching equipment and a sender responsive to the alternating current impulses from the first mentioned sender to set this last mentioned sender in accordance with the digits represented by said impulses and to set the automatic switching equipment on a terminal representing the digits, automatic switching means, means actuated when said terminal is found for releasing the sender and automatic switching equipment and connecting the toll line with said automatic switching means, means actuated when a toll line is connected with the automatic switching means for transmitting an impulse consisting of a high frequency alternating current interrupted at a low fre-

quency rate over the toll line towards the cord circuit, means at the originating end of the toll line and in the cord circuit responsive to said last mentioned impulse for actuating said signal at the cord circuit to indicate that the selection of a subscriber's line may begin, means responsive to alternating current impulses received from the impulse transmitting means associated with the cord circuit for actuating said automatic switching means to connect the toll line with a subscriber's line corresponding to the digits represented by said alternating current impulses, means actuated when the wanted subscriber's line is reached for transmitting an impulse consisting of a high frequency alternating current interrupted at a low frequency rate over the toll line towards the cord circuit and means at the originating end of the toll lines and in the cord circuit for disabling the signal.

20. In a telephone system, toll lines, subscribers' lines, a circuit, means associated with said circuit for transmitting current impulses of different characteristics, switching means adapted to be associated with one end of said circuit responsive to impulses of one character for selecting a toll line, switching means associated with one end of the toll line responsive to impulses of the other character for selecting a subscriber's line and means associated with the opposite end of said circuit responsive to impulses of another character for selecting a subscriber's line.

21. In a telephone system, toll lines, subscribers' lines, a cord circuit including a dialing device and means for transmitting direct and high frequency alternating current impulses by the operation of said dialing device, switching mechanism available to said cord circuit and responsive to direct current impulses therefrom for selecting toll lines, switching mechanism available to the opposite end of any one of said toll lines, means for seizing a switching mechanism at the opposite end of a selected toll line and means associated with a seized switching mechanism for translating alternating current impulses transmitted over the toll line from the cord circuit into direct current impulses and for actuating said switching mechanism by means of said direct current impulses to select a subscriber's line.

22. In a telephone system, toll lines, subscribers' lines, a cord circuit including means for transmitting direct and alternating current impulses, a signal associated with said cord circuit, switching mechanism available to said cord circuit and responsive to direct current impulses therefrom for selecting toll lines, switching mechanism available to the opposite end of any one of said toll lines, means for seizing a switching mechanism at the opposite end of a selected toll

- line, means associated with a seized switching mechanism for translating alternating current impulses transmitted over the toll line from the cord circuit into direct current impulses and for actuating said switching mechanism by means of said direct current impulses to select a subscriber's line, and means for actuating said signal when a toll line is selected for disabling said signal 5
- 10 when the alternating current impulses have all been received and for again actuating said signal when the subscriber's line has been reached.
23. In a telephone system, toll lines, subscribers' lines, a cord circuit including means for transmitting direct and alternating current impulses, a signal associated with said cord circuit switching mechanism available to said cord circuit and responsive 15
- 20 to direct current impulses therefrom for selecting toll lines, switching mechanism available to the opposite end of any one of said toll lines, means for seizing a switching mechanism at the opposite end of a selected toll line, means associated with a seized switching mechanism for translating alternating current impulses transmitted over the toll line from the cord circuit into direct current impulses and for actuating said 25
- 30 switching mechanism by means of said direct current impulses to select a subscriber's line, means for actuating said signal when a toll line is selected, for disabling said signal when the alternating current impulses 35
- 35 have all been received and for again actuating said signal when the subscriber's line has been reached, and means associated with the cord circuit for transmitting a ringing signal to the subscriber of the selected line 40
- 40 and means for disabling the first mentioned signal when the subscriber seizes his line.
24. In a telephone system, toll lines, subscribers' lines, a cord circuit including a dialing device for transmitting impulses, a signal, switching means available to said cord circuit and responsive to impulses therefrom for selecting an idle toll line, means including a switching mechanism associated with a toll line when seized and responsive to impulses from the cord circuit for selecting a subscriber's line, means for transmitting an impulse over a selected toll line when said last mentioned switching mechanism has been seized, said impulse 45
- 55 consisting of a high frequency alternating current interrupted at a low frequency rate, means responsive to said impulses for actuating said signal, means for transmitting an identical impulse over said toll line when all the impulses for selecting a subscriber's line have been received and means responsive to this second impulse for disabling said signal, means for transmitting an identical signal over the toll line when the subscriber's line has been reached and means re- 50

- sponsive to this last mentioned impulse for again operating said signal, means for transmitting a ringing signal from said cord circuit to the subscriber of the selected line, said signal consisting of a high frequency alternating current interrupted at a low frequency rate different from the low frequency rate at which the signal control impulses are interrupted, means for transmitting a signal control impulse over the toll line when the calling subscriber answers the connection and means responsive to said last mentioned control signal impulse for disabling the signal at the cord circuit.
25. In a telephone system, a plurality of exchanges, toll lines interconnecting said exchanges, means at the first exchange for selecting one of several available routes through one or more intermediate exchanges to a terminating exchange comprising selecting mechanism adapted to be actuated to select an idle toll line from the toll lines representing one route and if all of said toll lines are engaged to select an idle toll line in another group of toll lines representing another route, means at any intermediate exchange for selecting one of several available routes through succeeding intermediate exchanges or directly to said terminating exchange comprising selecting mechanism adapted to be actuated to select an idle toll line in one group of toll lines representing one route and if all of said toll lines are engaged to select an idle toll line in another group representing another route and means at the first exchange for producing direct current impulses for actuating the selecting mechanism thereat translating said impulses into alternating current impulses for transmission over the selected toll line leading to the next intermediate exchange and means at each intermediate exchange for receiving said alternating current impulses, translating them into direct current impulses, actuating thereby the selecting mechanism thereat, retranslating said direct current impulses into alternating current impulses and transmitting said impulses over the associated toll lines to a succeeding exchange.
26. In a telephone system, a plurality of exchanges, toll lines interconnecting said exchanges, means at the first exchange for selecting one of several available routes through one or more intermediate exchanges to a terminating exchange comprising selecting mechanism adapted to be actuated to select an idle toll line from the toll lines representing one route and if all of said toll lines are engaged to select an idle toll line in another group of toll lines representing another route, means at any intermediate exchange for selecting one of several available routes through succeeding intermediate exchanges or directly to said terminating exchange comprising selecting mechanism

- adapted to be actuated to select an idle toll line in one group of toll lines representing one route and if all of said toll lines are engaged to select an idle toll line in another 5 group representing another route and means at the first exchange for transmitting alternating current impulses over the toll lines through the intermediate exchanges to the terminating exchange, and switching means 10 at the terminating exchange responsive to said impulses for selecting a wanted subscriber's line.
27. In a telephone system, a plurality of exchanges, toll lines interconnecting said exchanges means at the first exchange for selecting one of several available routes through one or more intermediate exchanges to a terminating exchange comprising selecting mechanism adapted to be actuated to 15 select an idle toll line from the toll lines representing one route and if all of said toll lines are engaged to select an idle toll line in another group of toll lines representing another route means at any intermediate 20 exchange for selecting one of several available routes through succeeding intermediate exchanges and directly to said terminating exchange comprising selecting mechanism

adapted to be actuated to select an idle toll line in one group of toll lines representing one route and if all of said toll lines are engaged to select an idle toll line in another group representing another route, means at the first exchange for transmitting alternating current impulses over the toll lines 35 through the intermediate exchanges to the terminating exchange, switching means at the terminating exchange responsive to said impulses for selecting a wanted subscriber's line, a supervisory signal at the first exchange, means for controlling said signal by means of alternating current impulses transmitted over the connected toll lines to indicate when the directive alternating current impulses are to be sent, to indicate when 40 the subscribers' lines have been selected thereby and to indicate when the selected subscriber answers the call, and means for transmitting alternating current impulses over the connected toll lines for the originating exchange to call the selected subscriber.

In witness whereof I hereunto subscribe my name this 5th day of August, A. D., 1924.

PAUL B. MURPHY.
